CAR JOURNAL LUBRICATOR

Aldred J. Jones, Chicago, Ill.

Application December 13, 1935, Serial No. 54,231

7 Claims. (Cl. 308—87)

This invention relates to car journal lubricators.

One of the objects of the invention is to simplify and otherwise improve upon devices of this character.

Another object is to eliminate the use of springs in a car journal lubricator.

Another object is to reduce the number of parts of such devices.

Another object is to produce a lubricator which is capable of functioning properly in restricted spaces.

Another object is to provide a lubricator having a pad of novel construction.

Other objects and advantages will appear in the course of the following specification, and with all of such objects and advantages in view, this invention consists in the several novel features hereinafter fully set forth and claimed.

The invention is clearly illustrated in the drawings accompanying this specification, in which:

Fig. 1 is a view, partly in end elevation and partly in vertical cross-section, of a journal box equipped with a lubricator embodying one form of the invention, the section being taken on the line 1—1 of Fig. 2;

Fig. 2 is a view, partly in side elevation and partly in vertical section, taken on the line 2—2 of Fig. 1;

Fig. 3 is a detail, vertical cross-section, through the lubricator and through fragments of the journal box and axle;

Fig. 4 is a detail, fragmental side elevation of the pad;

Fig. 5 is a side elevation, illustrating a slightly modified form of the invention;

Fig. 6 is a side elevation, illustrating another modification;

Fig. 7 is a side elevation of another modification;

Fig. 8 is an end elevation of the form of lubricator seen in Fig. 7;

Fig. 9 is a view partly in end elevation and partly in cross-section of fragments of a journal box and another form of the invention;

Fig. 10 is a fragmental plan of the lubricator seen in Fig. 7 partly broken out; and

Fig. 11 is a front elevation thereof.

Referring to said drawings, and first to Figs. 1 to 4, inclusive, the reference character 10 designates a railway car journal box of conventional form, in which is contained the brass bearing block 11, which bears upon the axle 12. As is customary, an oil well 13 is provided in the bottom of the journal box.

Adjacent the rear wall 14 of the journal box is an upright flange or web 15 which, together with the rear wall, provides a groove 16 for the dust guard. The rear wall and web are formed

with aligned circular openings through which the axle enters the journal box. The front wall 17 is provided with the usual inspection opening, through which the lubricator is inserted and installed in the journal box. The parts described are of standard construction and require no further description so far as this specification is concerned.

Aligned apertures 18, 19 are formed in the front wall 17, and web 15, below the axis of the axle, at places adjacent one or both side walls 20 of the journal box, in which apertures are received the ends of a horizontally extending supporting rod 21 which is fastened in place on said walls of the box by nuts 22, 23, threaded on one end of the rod and bearing against the inner and outer faces of the front wall or against interposed washers 24, as shown. The supporting rod may, of course, be mounted on the box in any suitable manner.

Swingably mounted on the supporting rod 21 is a pad holder 25, on which is suspended an oil applying pad 26. The lower end of the pad is submerged in the oil contained in the well and its upper end portion is pressed against the axle with a light pressure. Oil is carried up the pad by capillary attraction and is applied to the axle. The pad holder desirably comprises a horizontal pressure bar 27, from which arms 28 extend to the supporting rod 21, where each is formed with an elongated eye 29 through which the supporting rod extends. Two supporting arms 28 are shown in Figs. 1 to 3; they may be formed as part of the pressure bar 27, or they may be formed as separate pieces spot-welded thereto. As a preference, however, a pivotal connection is provided between the pressure bar and the supporting arms. Conveniently, the metal of the pressure bar is struck up at two aligned spaces to form eyes 46, in which a pin 47 is held, and the supporting arms are formed with an eye 48 through which the pin 47 extends. This arrangement permits the pressure bar and the contacting portion of the pad to adjust itself to the curvature of the axle, despite the exact location of the supporting rod 21. Desirably the opening in the eye 48 is slightly larger than the diameter of the pin 47, thereby permitting the pressure bar and pad to rock in a horizontal plane and thereby follow any rolling or radius movements of the axle that occur while the car is traveling around curves. The elongated eyes 29 on the supporting arms also facilitate such movement of the pad holder.

The supporting rod may be provided with spaced shoulders 50 thereon, between which the supporting arms are located. The shoulders retain the pad holder thereon and facilitate the insertion and removal of the lubricator to and from the journal box. The shoulders may be omitted if desired.

Extending down from the pressure bar 27 is a lever arm 30, formed as a part of the pressure bar or it may be formed as a separate piece, spot-welded or rigidly secured thereto. As shown, the 5 lever arm 30 and the two supporting arms 28 are formed in one piece struck up with suitable dies. The three arms extend from a main part 49 which contains the eye 48. The lever arm extends below the supporting rod 21 and thence laterally under- 10neath the axle where it carries a counterweight 31, desirably adjustably secured along the length of the arm by a screw 32. The end of the lever arm is bent up slightly or otherwise provided with means to prevent the weight from coming off the 15 arm. An opening 45 is formed in the pad to permit the lever arm to pass from one side thereof to the other.

The supporting arms 28 and lever arm 30 form a knee lever fulcrumed upon the rod 21. The 20 lever arm serves to lightly press the upper end of the pad against the side of the axle, regardless of the floating movements of the axle in the journal box. Desirably the lever arm is formed of resilient material, whereby it may be bent, if necessary, to pass by the axle flange when installing 25 the lubricator in the journal box. Ordinarily the lubricator is inserted through the inspection opening of the journal box.

The pad is of novel construction. Desirably it 30 is formed of an absorbent body, composed of a plurality of cotton rovings 33, suitably fastened together by rows of stitches 34. The body is enclosed in a covering 35 formed of textile fabric doubled over the body with its ends sewed together and with its side edges lapped over the body and secured by rows of stitches 36. Adjacent the upper end of the pad a section of the covering material is omitted across one face of the pad, thereby exposing the absorbent body portion, as 35 at 37. The exposed portion of the pad body comprises the part which contacts with the axle and delivers the oil thereto.

On the end portion 40 of the pad, beyond the exposed part 37, is secured an attachment strip 45 38, the top and bottom edges of which are bent up to form overhanging edges which provide grooves 39 in which the top and bottom edges of the pressure bar are received. Desirably the attachment strip is fastened to the end portion 40 of the pad 50 by staples 41. Projecting from the ends of the attachment strip are tongues 42, bent over the ends of the pressure bar to secure the attachment strip and therewith the pad on the pad holder.

The end portion 40 of the pad is doubled back on 55 the pad along the line 43 and is fastened to the main portion of the pad by rows of stitches 44, 44. This brings the attachment strip on the side of the pad opposite the exposed part of the body. The pad is attached to the pressure bar by sliding 60 the pressure bar through the grooves in the attachment strip and bending the tongues around the ends of the pressure bar. Desirably the attachment strip is formed of brass to avoid wear 65 on the axle flanges, inasmuch as the bent up tongues are likely to rub against the flanges.

With the use of the above described pad, an ample quantity of lubricating oil is always delivered to the axle. The textile fabric covering or 70 sheath prevents dust, dirt or other foreign particles from entering the absorbent body portion of the pad. The textile fabric covering permits any dust, dirt or other foreign particles to free themselves from the covering when the pad is cleaned. If desired, the lower end of the cover-

ing may be left open, thereby exposing the lower ends of the rovings directly to the lubricating oil.

In the modified form of the invention, illustrated in Fig. 5, the pad holder 25^a has two lever arms 30^a and one supporting arm 28^a, the supporting arm being centrally located on the pressure bar and the lever arms being disposed at the sides thereof. The several arms are shown as spot-welded to the pressure bar 27^a. Slots 45^a 5 may be provided in the pad in alignment with the lever arms in order that they may extend from one side of the pad to the other. In all other respects the lubricator may be constructed in substantially the same manner as the one illustrated in Figs. 1 to 3.

In the modified form, illustrated in Fig. 6, instead of using a grooved attachment bar removably attached to the pressure bar, the pad holder 25^b has a single flat pressure bar 51, which is directly fastened to the pad by staples or the like, 20 and the bar is struck up with a pair of eyes 52, which co-operate with the eye 48, on the supporting arms 28, and a cotter pin 53, to provide the swivel connection between the bar 51 and supporting arms 28. This arrangement permits of 25 the independent tilting movement of the pressure bar and pad and also permits removal and replacement of the pad by merely withdrawing the cotter pin from the eyes.

In the modified form illustrated in Figs. 7 and 30 8, the pad holder 25^c is composed of a single piece comprising the pressure bar 54, supporting arms 55 and the lever arms 56. In this form of the invention the pad 26 is directly secured to the pressure bar 54 as by rivets 57. The supporting 35 arms are widely spaced, thereby affording a long bearing on the supporting rod and the weight serves to lightly press the pad against an axle.

In the form illustrated in Figs. 9, 10 and 11, the supporting arms 58 of the pad holder 25^d are 40 formed of strips of resilient metal, and are shown as rigidly fastened to the side wall 20 of the journal box by bolts and nuts 59. The pressure bar 60 is fastened to the pad by rivets, staples or the like, and is swiveled upon the upper ends of the resilient arms so that the pressure face of the pad may adjust itself to the curvature of the axle. The swivel connection may comprise aligned, horizontally extending, outwardly struck up loops 61, formed on the pressure bar and eyes 62 formed 45 on the upper ends of the resilient arms 58, curled around the loops. The loops may be slightly longer than the width of the arms, thereby permitting the pad to move laterally of the arms so as to follow any lateral or endwise movements of 50 the axle. With the use of resilient supporting arms the pad is free to accommodate itself to any rolling or radius movements of the axle that occurs when the car passes around curves in the track, since either resilient arm is free to be 55 pressed back more or less.

In connection with all of the forms of the invention illustrated, it is to be observed that the entire pad is disposed between the axle and the point of support for the pad holder. The result 60 is that the weight of the oil saturated pad, in many instances, is sufficient to apply the necessary pressure against the axle, and the weighted lever is used merely to augment the pressure where greater pressure is required, than that obtained by the weight of the oil saturated pad. At the place where the lever arm passes through the pad, the latter may rest on the arm, in which case the weighted arm serves to swing the pad holder, together with the upper end of the pad, toward 70 75

the axle, or the weight may be omitted from the arm and the pad may be draped over the arm, thereby serving to increase the pressure of the pad against the axle. In situations where a light pressure is desired, the saturated wick alone, disposed laterally of the point of support of the wick holder, on that side thereof between the axle and point of support of the wick holder, has been found ample to accomplish the desired result.

10 It is to be observed that the pad holder is free to slide along the supporting rod, thereby enabling the pad to accommodate itself to any lateral or endwise movement of the axle. It is also to be observed by reason of the arrangement of 15 the attaching means between the attachment strip and pad there are no staples or other fastening means in the main portion of the pad which would otherwise compress the pad and restrict the flow of oil past the staples. In other 20 words, the free flow of oil by capillary attraction is permitted throughout the pad to the place where it applies the oil to the axle.

While the invention has been shown and described in connection with a car journal, it is to 25 be understood that its use is not limited thereto, as it can be used with other journal bearings.

I claim as new and desire to secure by Letters Patent:

1. A journal lubricator comprising in combination an axle, a horizontal fulcrum element extending parallel with and laterally of the axle, a support for said fulcrum element, an upwardly inclined pad holder fulcrumed at its lower end on said fulcrum element and inclined in a direction 35 toward the axle, a lever arm rigid with and extending laterally from the pad holder in a direction toward the lower side of the axle, and a pad secured at its upper end to the upper end of the pad holder and depending entirely on the side of the pad 40 holder from which the lever arm extends, whereby the pad co-operates with the lever arm to press the upper end of the pad against the axle.

2. A journal lubricator, comprising in combination an axle, a horizontal rod extending parallel 45 with and laterally of the axle, a support for the rod, an upwardly inclined pad holder fulcrumed at its lower end on said rod and inclined in a direction toward the axle, a weighted lever arm rigid with and extending laterally from the pad holder in a direction toward the lower side of the 50 axle, and a pad secured at its upper end to the upper end of the pad holder and depending therefrom entirely on the side of the pad holder from which the lever arm extends, whereby the pad co-operates with the lever arm to press the upper end of the pad against the axle.

3. A journal lubricator, comprising in combination an axle, a horizontal rod extending parallel with and laterally of the axle, a support for said 55 rod, an upwardly inclined pad holder fulcrumed at its lower end on said rod and inclined in a direction toward the axle, a lever arm rigid with and extending laterally from the pad holder in a direction toward the lower side of the axle, a 60 weighted block adjustably mounted on said lever arm, and a pad secured at its upper end to the upper end of the pad holder and depending therefrom entirely on the side of the pad holder from which the lever arm extends, whereby the pad co- 65 operates with the lever arm to press the upper end of the pad against the axle.

4. A car journal lubricator, comprising a horizontally extending supporting rod adapted to be 70 removably supported within a journal box, said

rod having a pair of spaced shoulders thereon, an upwardly extending pad holder fulcrumed at its end on said rod between said shoulders and being slidably movable between said shoulders, said pad holder being provided with a lever arm 5 extending laterally therefrom, and a pad attached at its upper end to the upper end of the pad holder and depending freely therefrom entirely on the side thereof containing the lever arm, all of said elements comprising a unit capable 10 of being inserted in a journal box, or removed therefrom as a unit.

5. A car journal lubricator, comprising an axle, a horizontally extending rod supported parallel with the axle and at one side thereof, a swingable, 15 upwardly extending pad support fulcrumed at its lower end on said rod and being slidable thereon within given limits, said pad supports inclining toward the axle and having a lever arm projecting laterally therefrom in the direction of the 20 axle, a pressure bar swiveled on a horizontal axis on the upper end of the pad support and being capable of rocking in vertical and horizontal planes, whereby to adjust itself to the floating movement of the axle, and a pad secured at its 25 upper end to said pressure bar in position to contact with the axle and depending freely from said pressure bar entirely on that side of the pad support containing the lever arm, said pad co-operating with the lever arm to swing the 30 upper end of the pad support, together with the pressure bar and pad, toward the axle.

6. A journal lubricator comprising in combination a journal box and an axle journaled therein, a horizontal rod mounted in the journal box parallel 35 with and located at one side of the axle, a swingable upwardly extending pad supporting arm fulcrumed at its lower end on said rod, and normally inclined toward the side of the axle, a pressure bar shiftable in a line parallel with the 40 axle, said supporting arm and pressure bar having aligned ears, a pin removably secured in said ears and forming a removable swivel connection between the pressure bar and pad supporting arm, whereby the pressure bar may rock on the 45 pin and may be disconnected from the pad supporting arm by the removal of the pin, and a pad fixedly attached to the pressure bar, the latter providing a stiff backing for the pad, whereby the pressure bar and pad may be shifted 50 as a unit.

7. A journal lubricator comprising in combination a journal box, an axle journaled therein and having lateral play therein, a horizontal fulcrum element extending parallel with and located at one side of the axle, and supported in the journal box, an upwardly inclined pad supporting arm fulcrumed at its lower end on said fulcrum element and normally inclined in a direction toward the axle, and adapted to be swung laterally by the laterally movable axle, a pressure bar on the upper end of said arm, and disposed laterally thereof on that side which is adjacent the axle, and a pad fixedly fastened, from edge to edge, to the pressure bar on that side thereof which is adjacent the axle and depending therefrom in a vertical plane located between the fulcrum element and the axle, said pad being adapted to be saturated with oil, whereby the downward pull of the pad on the pressure bar tends to swing the 65 pad supporting arm and therewith the pressure bar and pad toward the axle.
